(57) CLAIM

The ornamental design for a pen-shaped scissors, as shown and described.

DESCRIPTION

FIG. 1 is a perspective view of the pen-shaped scissors showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof when the pen-shaped scissors is not in use; and,

FIG. 10 is a perspective view thereof when a cap is disposed on the pen-shaped scissors.

The broken lines in the drawings illustrate portions of the pen-shaped scissors that form no part of the claimed design.
